(57) **CLAIM**

The ornamental design for a baby changing pad, as shown and described.

DESCRIPTION

FIG. 1 is a top perspective view showing the baby changing pad in an expanded state, showing my new design;

FIG. 2 is a bottom perspective view showing the baby changing pad in an expanded state;

FIG. 3 is a front view showing the baby changing pad in an expanded state;

FIG. 4 is a rear view showing the baby changing pad in an expanded state;

FIG. 5 is a left side view showing the baby changing pad in an expanded state;

FIG. 6 is a right side view showing the baby changing pad in an expanded state;

FIG. 7 is a top view showing the baby changing pad in an expanded state;

FIG. 8 is a bottom view showing the baby changing pad in an expanded state;

FIG. 9 is a left side perspective view showing the baby changing pad in a partially closed state;

FIG. 10 is an enlarged detail view of area 10 in FIG. 1;

FIG. 11 is an enlarged detail view of area 11 in FIG. 1; and,

FIG. 12 is an enlarged detail view of area 12 in FIG. 2.

The broken lines in the drawings illustrate the portions of the baby changing pad, which form no part of the claimed design.

The dash-dot-dash broken lines encircling the enlarged views are for annotative purposes only and form no part of the claim thereof.

1 Claim, 12 Drawing Sheets
